EMILE LOUIS ALBERT PAUMIER, OF PARIS, FRANCE.

MACHINE GUN.

Application filed March 5, 1918. Serial No. 220,622.

To all whom it may concern:

Be it known that I, EMILE LOUIS ALBERT PAUMIER, a citizen of the Republic of France and a resident of Paris, France, 5 engineer, have invented new and useful Improvements Relating to Machine Guns, which invention is fully set forth in the following specification.

This invention has for its object mechanism which allows a machine gun or twin machine guns to be operated by a driven shaft. The driven shaft may be the screw shaft of an aeroplane and in this case the invention allows fire to be so regulated that 15 the bullets always pass between the blades of the screws or propellers.

The machine gun may be of any type, but is preferably a type in which the barrel has a short recoil.

20 The gun is operated, not by utilizing the energy of the explosion gases or that of the recoil, but as explained by an outside motor. It is therefore necessary to slightly modify the machine gun employed in such a manner 25 that it is no longer automatic but is operated when required by the mechanism hereinafter described which while operating the gun causes the firing of the bullet to depend on the position of the screw.

30 Broadly stated the invention comprises a shaft driven by the propelling engine of an aeroplane and mechanism actuated by said shaft for imparting motion to the movable parts of a machine gun at the proper time 35 to effect firing of the gun between the blades of the propeller.

In the accompanying illustrative drawings, Fig. 1 is a sectional elevation of the 40 cam shaft. Fig. 2 shows the cocking mechanism and the arrangement for disconnecting it; Fig. 3 is a section on the line Z—Z of Fig. 2; Fig. 4 shows the safety mechanism. Fig. 5 shows mechanism actuating the 45 firing tumbler and Fig. 6 shows a cam shaft applied to a twin gun.

Fig. 7 is a diagrammatic view of the mechanism described applied to a machine gun of the Vickers type having a short recoil. Machine guns of this type comprise a 50 movable breech block *a*, carrying a firing pin and sliding in a breech casing *b*, the breech block being connected by a connecting rod *c* to a crank *d*; the crank *d* is connected to the movable barrel *e* by two recoil plates *f*. 55 A coiled spring not illustrated brings the

breech block and the assemblage of movable parts to the front position.

Fig. 8 is a plan of the screw showing at what moment it is advisable to fire.

Fig. 9 is a schematic view showing the 60 mechanism of the present invention and the movable parts of the machine gun locked in extreme recoil position: and

Fig. 10 is a similar schematic view showing the same parts in the position occupied 65 at the instant when the gun is fired.

The driven shaft which may be the screw shaft of an aeroplane or a shaft parallel to it and driven at the same speed as it is shown at 1 in Fig. 1; is connected to a 70 cam shaft 2 at right angles to it by a connection which has the minimum of play, for example, a worm 4 driving a worm wheel 3.

The cam shaft 2 is carried by bearings 5 and 5¹ formed on flanges 6 and 6¹ fixed 75 beneath the gun breech. A cocking cam 8, a safety cam 9 and a firing eccentric 10 are mounted and keyed to the shaft 2.

11, Fig. 2, is a spring which maintains a 80 roller 12 mounted on the end of one of the arms of a cocking lever 13 in contact with the cam 8; the other arm 14 of the lever 13 bears against the forward surface of a roller 15 mounted at the end of the crank *d*. The roller 12 when raised by the cam 8 causes 85 the assemblage of the movable parts to move rearwards and so moves the breech block. The fall of the roller 12 allows the coiled spring to move the movable parts forward 90 and to close the breech.

As indicated in Fig. 3 the roller 12 is connected to the cocking lever 13 by a strap 16 provided with a security rivet 17 of mild steel which shears when subjected to an abnormal strain.

95 The eccentric 10, Fig. 5, controls the firing tumbler 22 by means of a rod 23 jointed at 24 to a bent lever 25 whose pivot 26 is fixed in a suitable position of the breech casing (see Fig. 9). Firing is effected directly 100 after the passage of the screw blade by the firing eccentric 10. Firing is preferably effected when the rear edge *g* of the screw blade *h*, Fig. 8, forms with the vertical plane containing the axis of the barrel *i* 105 an angle of about 10°. *j* is a sector showing the space for the passage of the bullets; estimating it at 20° there will remain in front of the forward edge *k* of the second blade *l* a security sector of about 135°. The 110

arrow *m* shows the direction of motion of the screw.

18, Fig. 4, is a roller on the end of a bent lever 19 and maintained in contact with the cam 9 by a spring 20. The arm 21 of the lever 19 whose end is cut at a sharp angle, engages a notch formed beneath one of the recoil plates *f* and thus takes the pull of the coiled spring. Once per rotation of the 10 cam, the arm 21 moves downwards and liberates the recoil plate to allow the movable breech block to close and the gun to fire.

The cocking lever 13 is pivoted at 7 and has an extension 29 which can be acted upon 15 by an eccentric boss 28 on a handle 27 for immobilizing the lever 13 exactly at the rear end of its travel; thus providing means by which the rotation of the driving shaft is prevented from always fully operating 20 the cocking lever 13. To limit the downward movement of the handle 27 the stop 27' is provided.

The firing eccentric 10 and the safety lever 19 make such small movements that 25 they may be actuated without inconvenience. It is well, however, to allow some small play between the end of the arm 21 and the bottom of the notch on the recoil plate *f*; this can be effected by suitably shaping the 30 eccentric boss 28.

The apparatus works as follows after the cams and eccentrics have been carefully placed and immobilized on the shaft 2:

When the pilot wishes to fire, he first 35 raises the handle 27 to allow the cocking lever 13 to retract intermittently the breech-block for firing purposes. With the parts positioned as shown in Fig. 7, rotation of cam shafts 2 causes cam 8 to rock pivoted lever 13 rearwardly, which by its engagement with roller 15 on the projecting end of crank *d* moves the breech mechanism and barrel *e* rearwardly against the tension of the recuperator spring (not shown). During 40 rearward movement of the breech mechanism and barrel, the firing pin *a* is cocked in the usual manner and the arm 21 of lever 19 engages the notch of recoil plate *f*, the tension of spring 20 causing rotation of lever 19 at the proper moment to effect this engagement.

The continued rotation of cam shaft 2 causes cam 9 to release arm 21 from engagement with the recoil plate, whereupon the 55 recuperator spring returns the breech mechanism and barrel to the forward or firing position. Shortly after the parts reach the firing position, the cam 10 actuates the rod 23 to rock bent lever 25 and thereby release 60 the sear 22 from engagement with the tumbler, whereby the firing pin is operated to fire the gun. It will, of course, be understood that, during the operations above described, the gun is loaded and the empty 65 cartridge case ejected by the usual well

known mechanism. After firing, the pilot again moves the handle 27 to lock the movable parts in the recoil position and so avoids wear of the mechanism and absolutely prevents the gun being fired even if by inadvertence he still pulls the flexible cable. 70

Fig. 6 relates to an arrangement for a twin machine gun. The guns are arranged parallel to the axis of the aeroplane, their barrels are shown at 30 and 30¹ one on each 75 side of the plane of symmetry of the aeroplane. A sighting collimator 31 is fixed in this plane. The cam shaft 2 is in this case carried by four flanges forming below each gun two casings 32, 32¹, each containing a 80 cocking cam 8, 8¹, a safety cam 9, 9¹, and a firing eccentric 10, 10¹. 3 is the worm wheel 85 gearing with the shaft of the screw.

In the one barrel gun it is advantageous to so select the sizes of the gearings that the 85 gun fires a shot at each turn of the screw; in this manner if the motor turns at 1200 revolutions a minute, the gun will fire 600 rounds in the same time.

In the twin gun the arrangement is usually such that the cams control fire alternately from left to right; thus a shot will be fired at each second revolution of the 90 screw and the fuselage of the machine will not be subjected to too violent strain. 95

Claims:

1. In a rapid-fire gun mounting for aeroplanes, the combination of a breech-block spring-pressed to firing position, a shaft driven by the propelling engine of the aeroplane in synchronous relation with the propeller shaft thereof, and mechanism actuated by said driven shaft to retract intermittently the breech-block to recoil position against the action of its spring, the rotative movements of the two shafts being synchronized so that the intervals between the propeller blades register with the line of fire on the return of the breech-block to firing position. 100

2. In a rapid-fire gun mounting for aeroplanes, the combination of a breech-block spring-pressed to firing position, a shaft driven by the propelling engine of the aeroplane in synchronous relation to the propeller shaft thereof, a cam on the driven shaft, and a pivoted lever oscillated by the cam to retract intermittently the breech-block to recoil position against the action of its spring, the rotative movements of the two 105 shafts being synchronized so that the intervals between the propeller blades register with the line of fire on the return of the breech-block to firing position. 110

3. In a rapid-fire gun mounting for aeroplanes, the combination of a breech-block spring-pressed to firing position, a shaft driven by the propelling engine of the aeroplane in synchronous relation with the propeller shaft thereof, mechanism actuated by 115

- a said driven shaft to retract intermittently the breech-block to recoil position against the action of its spring, and mechanism operated by said driven shaft to actuate the 5 firing device on return of the breech-block to firing position, the rotative movements of the two shafts being synchronized so that the intervals between the propeller blades register with the line of fire at the time of 10 discharge.
4. In a rapid-fire gun mounting for aeroplanes, the combination of a breech-block spring-pressed to firing position, a shaft driven by the propelling engine of the aeroplane in synchronous relation with the propeller shaft thereof, a cam on the driven shaft, a pivoted lever oscillated by said cam to retract intermittently the breech-block to 15 recoil position against the action of its spring, a second cam on the driven shaft, a second pivoted lever oscillated by said cam to actuate the firing device on return of the breech-block to firing position, a third cam on the driven shaft, and a third pivoted lever oscillated by the third cam to release the safety catch of the breech-block preliminary to complete closing of the latter, the rotative movements of the two shafts being synchronized so that the intervals between the propeller blades register with the 20 line of fire at the time of discharge.
5. In a rapid-fire gun mounting for aeroplanes, the combination of a breech-block spring-pressed to firing position, a shaft 30 driven by the propelling engine of the aeroplane in synchronous relation with the propeller shaft thereof, a cam on the driven shaft, a pivoted lever oscillated by said cam to retract intermittently the breech-block to 35 recoil position against the action of its spring, a second cam on the driven shaft, a second pivoted lever oscillated by the second cam to actuate the firing device on return of the breech-block to firing position, a third cam on the driven shaft, and a third pivoted lever oscillated by the third cam to release the safety catch of the breech-block preliminary to complete closing of the latter, the rotative movements of the two shafts being synchronized so that the intervals between the propeller blades register with the 40 line of fire at the time of discharge.
